CLAIM

The ornamental design for a T-handle for a torque-applying tool, as shown and described.

DESCRIPTION

FIG. 1 is a top perspective view of the T-handle for a torque-applying tool showing our new design;

FIG. 2 is a top plan view thereof;

FIG. 3 is a front elevational view thereof; the rear elevation view is identical to FIG. 3;

FIG. 4 is a right end elevational view thereof; the left end elevational view is identical to FIG. 4; and,

FIG. 5 is a bottom plan view thereof.
